(57) **CLAIM**

I claim the ornamental design for a front plate for an electronics enclosure, as shown.

DESCRIPTION

FIG. 1 is a side perspective view of the front plate for an electronics enclosure showing my new design;

FIG. 2 is an opposite side perspective view thereof;

FIG. 3 is a front elevational view thereof;

FIG. 4 is a top plan view thereof;

FIG. 5 is a rear elevational view thereof;

FIG. 6 is a bottom plan view thereof;

FIG. 7 is a right side elevational view thereof; and,

FIG. 8 is a left side elevational view thereof.

The broken lines in the figures are for illustrative purposes only and form no part of the claimed design.
